LIFTING CLAMP

Gad Rosenbaum, Detroit, Mich.

Application May 31, 1951, Serial No. 229,213

7 Claims. (Cl. 294—104)

1

The present invention pertains to a novel clamp for lifting plates and similar heavy objects in shops, on construction jobs, and the like. The clamp is of the gravity type wherein the weight of the work piece causes a movable jaw to bind or clamp the piece against an opposite fixed jaw.

A serious defect of this type of clamp is that it becomes released as soon as the work piece is lowered into contact with the floor or ground, since the clamping action depends only on the weight of the piece. In handling heavy pieces the workmen are in constant danger of being injured by the slipping of the piece out of the clamp.

The principal object of this invention is to provide such a clamp wherein a positive clamping pressure is maintained on the work piece when the latter touches the floor or ground. The clamp body is slidably guided on a shackle, and the movement of the shackle operates a pivoted jaw through a link connection. The shackle body is slotted from its lower edge to receive the upper edge of the work piece, and the pivoted and fixed jaws extend into this slot. An upward force on the shackle, or relative downward movement of the clamp body, effects a clamping movement of the pivoted jaw.

According to this invention, the lower end of the shackle or a part connected thereto travels downward along the work-receiving slot when the upward pull on the shackle is released. This occurs of course when the work piece engages the floor or ground. At this time the part exposed in the slot comes into contact with the upper edge of the work piece and exerts an upward force on the shackle through the weight of the unsupported part of the clamp. The upward force on the shackle, as already indicated, produces a clamping action of the pivoted jaw, with the result that there is a positive clamping pressure on the work piece although it is in engagement with the floor or ground. Full release is obtained when desired merely by lifting the clamp manually.

The invention is fully disclosed by way of example in the following description and in the accompanying drawings in which:

Figure 1 is a side elevation of the device, showing the shackle approaching the work piece in the resting position of the latter;

Figure 2 is an end view;

Figure 3 is a section on the line 3—3 of Figure 2;

Figure 4 is an elevation of a modification, in

2

the same relative position as in Figure 1 and with one of the body plates removed;

Figure 5 is an elevation of another modification, with one of the body plates removed;

Figure 6 is a side elevation thereof, and

Figure 7 is a section on the line 7—7 of Figure 5.

Reference to these views will now be made by use of like characters which are employed to designate corresponding parts throughout.

In Figure 1 the device is shown as having a body consisting of a pair of spaced plates 1 and 2 between which the working parts of the clamp are assembled as will presently be described.

From the lower edge of the body, the plates are slotted upward as indicated by the numeral 3. In one of the lower corners of the body a fixed jaw 4 is secured between the plates by a pair of rivet head pins 5. The fixed pins passing through the plates at other points are also formed with rivet heads and held by cotter pins 6 and will not be described in detail. Rivets 7 hold the plates together near the upper corners.

A guide slot 8 is formed in each plate 1 and 2 above the slot 5 and substantially coaxial therewith. A shackle 9 has its lower end received between the plates 1 and 2 and between the pins 7. The shackle is guided in the slots 8 by means of a headed bolt 10 carried by the shackle and slidably received in the slots 8. The head of the bolt lies outside one of the plates, and the other end of the bolt is fitted with a nut 11 on the outer side of the other plate. The lower end of the shackle is enlarged at 12 in order to be exposed at the slots 3 when the pin 10 is at the bottom of the slots 8, for a purpose that will presently be described. The upper end of the shackle is formed with the usual eye 13.

In the lower corner of the body, opposite the jaw 4 is pivotally mounted a movable jaw 14 on a pivot pin 15. This jaw has a curved serrated face 16 extending into the slots 3, while the jaw 4 has a straight serrated face 17 also exposed at the slots 3.

The outward end of the jaw 14 is straddled by a pair of similar links 18 pivotally attached to the end by a pin 19 which, however, does not pass through the plates 1 and 2. The opposite ends of these links straddle the lower end of the shackle 9 and are pivotally mounted on the sliding pin 10. When the pin 10 is in the lower end of the slots 8, the links 18 space the face 16 of the jaw 14 from the face 17 of the jaw 4, and a work piece or plate 20 may be received between the faces. When the shackle 9 is lifted by its eye 13,

it rides upward relatively to the slots 8, carrying the pin 10 and the upper ends of the links 18 upward in the slots to turn the jaw 14 toward the jaw 4, whereby to clamp the member 20 between the jaws.

As previously indicated, the present lifting clamps of this character release the work piece when the latter is brought down to the floor, since the clamping effect is derived from the gravity pull of the work piece. With the clamp released and the work piece in vertical position although resting on the floor, the piece is not held securely and the handlers are in danger of being injured if a heavy plate slips out of the clamp. This condition does not occur in the clamp described herein. When the work piece 20 engages the floor and the pull is taken off the shackle, the parts ride downward along the slots 8, bringing the enlarged lower end 12 of the shackle across the slots 3 until it engages the upper end of the work piece. A slight upward pressure is thereby exerted on the shackle and, as previously described, this produces a clamping action of the jaws on the work piece. In another sense the pin 10 does not quite reach the bottom of the slots 8, so that the jaw 14 is not brought to its full open position. The clamp is fully released by manually lifting the body 4, 2.

The modification shown in Figure 4 differs from the previous construction only in the particulars that will now be described. The shackle 9' does not have its lower end 12' enlarged and does not become exposed at the slot 3' when the pin 10' drops to the bottom of the slots 8'. Instead, the upper ends of the links 18' are enlarged to form a downwardly facing shoulder 21 which obviously moves downward along the slots 3' as the pin 10' approaches the bottom of the slots 8'. This shoulder engages the work piece when the pull is taken off the shackle. An upward pressure on the sliding pin is thereby exerted, as described in connection with the pin 10, to maintain clamping pressure on the jaw 14' through the links 18'. As in the previous construction, this pressure is released when desired by manually lifting the body of the clamp.

In the first described construction the movement of the enlargement 12 on the upper edge of the work piece 20 during swivelling of the shackle 9 may be undesirable. Such scraping is avoided by the shoulder 21 of Figure 4 which projects beyond the lower end of the shackle 9'.

In Figure 5 is illustrated a form of the invention adapted to a somewhat different connection from the shackle to the movable cam. The body of the device, as previously, consists of a pair of plates 2' suitably secured together and having a work-receiving slot 22 extending from the lower edge as previously described. At one side of the slot is a fixed jaw 23, and at the opposite side is a pivoted jaw 24 mounted on a suitable pin 25.

Somewhat above the slot 22 is another pivot pin 26 on which is mounted a rocker arm 27. The shackle 28 is pivotally attached to one end of the rocker arm by a pin 29. From the other end of the rocker arm extends a pair of links 30 held thereto by a pin 31 and joined to opposite sides of the jaw 24 by another pivot pin 32.

At the upper end of the arm 27 is an enlargement 33, similar to the enlargement 21 of Figure 4, which extends across the upper end of the slot 22 when tension is taken off the shackle. The operation of this device is as described in connection with Figure 4. The difference lies in the working connection from the shackle to the

pivoted jaw, the link being guided by a rocker arm rather than by the slot of the previously described constructions. The plates 2' are held together by suitably located rivets 34 as well as the fixed pivot pins 25 and 29.

5 A similar light clamping action of either device is obtainable in lifting the work piece from a horizontal position, in which the work-receiving slot lies on a horizontal axis while the clamp is 10 being applied. The shackle is merely pushed by hand until the member exposed in the slot 21 engages the work piece with some pressure to actuate the pivoted jaw to a clamping position as previously set forth.

15 Although specific embodiments of the invention have been illustrated and described, it will be understood that various alterations in the details of construction may be made without departing from the scope of the invention as indicated by the appended claims.

20 What I claim is:

1. A lifting clamp comprising a body having a work-receiving slot extending from one edge thereof, a jaw carried by said body and extending into said slot from one side thereof, another jaw eccentrically pivoted to said body and extending into said slot at the other side, a shackle slidably connected to said body, an articulated connection between said shackle and pivoted jaw, for tightening said pivoted jaw by an outward pull on said shackle, and means movable vertically with said shackle and movable to a position between the ends of said slot on the clamp-releasing movement of said shackle, for engagement 25 with a work piece in said slot.

2. A lifting clamp comprising a body having a work-receiving slot extending from one edge thereof, a jaw carried by said body and extending into said slot from one side thereof, another jaw eccentrically pivoted to said body and extending into said slot at the other side, a shackle having a 30 slide pin-and-slot connection to said body, an articulated connection between said shackle and pivoted jaw, for tightening said pivoted jaw by an outward pull on said shackle, and means movable vertically with said shackle and movable to a position between the ends of said slot on the clamp-releasing movement of said shackle, for engagement 35 with a work piece in said slot.

3. A lifting clamp comprising a body having a work-receiving slot extending from one edge thereof, a jaw carried by said body and extending into said slot from one side thereof, another jaw eccentrically pivoted to said body and extending into said slot at the other side, a shackle slidably connected to said body, an articulated connection between said shackle and pivoted jaw, for tightening said pivoted jaw by an outward pull on said shackle, the end of said connection at said shackle having a portion movable to a position 40 between the ends of said slot on the clamp-releasing movement of said shackle, for engagement with a work piece in said slot.

4. A lifting clamp comprising a body having a work-receiving slot extending from one edge thereof, a jaw carried by said body and extending into said slot from one side thereof, another jaw eccentrically pivoted to said body and extending into said slot at the other side, a shackle having a 45 slide pin-and-slot connection to said body, an articulated connection between said shackle and pivoted jaw, for tightening said pivoted jaw by an outward pull on said shackle, the end of said connection at said shackle having a portion movable to a position between the ends of said slot on the clamp-releasing movement of said shackle, for engagement 50 with a work piece in said slot.

on the clamp-releasing movement of said shackle, for engagement with a work piece in said slot.

5. A lifting clamp comprising a body having a work-receiving slot extending from one edge thereof, a jaw carried by said body and extending into said slot from one side thereof, another jaw eccentrically pivoted to said body and extending into said slot at the other side, a shackle slidably connected to said body, an articulated linkage having pivotal connections to said shackle and pivoted jaw, for tightening said pivoted jaw by an outward pull on said shackle, the inner end of said shackle being movable to a position between the ends of said slot on the clamp-releasing movement of said shackle, for engagement with a work piece in said slot.

6. A lifting clamp comprising a body having a work-receiving slot extending from one edge thereof, a jaw carried by said body and extending into said slot from one side thereof, another jaw eccentrically pivoted to said body and extending into said slot at the other side, a shackle having a slideable pin-and-slot connection to said body, an articulated linkage having pivotal connection to said shackle and pivoted jaw, for tightening said pivoted jaw by an outward pull on said shackle, the inner end of said shackle being movable to a position between the ends of said slot on the clamp-releasing movement of said shackle, for engagement with a work piece in said slot.

30

7. A lifting clamp comprising a body having a work-receiving slot extending from one edge thereof, a jaw carried by said body and extending into said slot from one side thereof, another jaw eccentrically pivoted to said body and extending into said slot at the other side, a rocker arm pivoted to said body near the upper end of said slot, a link extending from said pivoted jaw to one end of said rocker arm, a shackle pivoted to the other end of said rocker arm, for tightening said pivoted jaw by an upward pull on said shackle, the last named end of said rocker arm having a portion movable to a position between the ends of said slot on the clamp-releasing movement of said shackle, for engagement with a work piece in said slot.
